2 SHEETS—SHEET 2.

UNITED STATES PATENT OFFICE.

THOMAS H. MARS, OF CHICAGO, ILLINOIS, ASSIGNOR TO FEDERAL ELECTRIC COMPANY, OF CHICAGO, ILLINOIS, A CORPORATION OF ILLINOIS.

CLOTHES WRINGER.

1,408,819.

Specification of Letters Patent. Patented Mar. 7, 1922.

Application filed February 19, 1920. Serial No. 359,980.

To all whom it may concern:

Be it known that I, THOMAS H. MARS, a citizen of the United States, and a resident of Chicago, in the county of Cook and State 5 of Illinois, have invented certain new and useful Improvements in Clothes Wringers; and I do hereby declare that the following is a full, clear, and exact description thereof, reference being had to the accompanying drawings, and to the letters of reference 10 marked thereon, which form a part of this specification.

This invention relates to improvements in clothes wringers, and consists of the matters 15 hereinafter described and more particularly pointed out in the appended claims.

One of the objects of the invention is to provide a clothes wringer embodying a safety mechanism which may be easily and 20 quickly actuated, to simultaneously release the tension of the compression springs at both ends of the wringer rolls.

Another object of the invention is to produce an improved construction which consists of but a few parts so arranged with 25 respect to each other as to provide a simple, strong and efficient clothes wringer.

These objects, as well as the several advantages of the invention, will more fully 30 appear as I proceed with my specification.

In the drawings:—

Figure 1 is a view in side elevation of a clothes wringer embodying my invention, the same being illustrated as used in connection with a power-operated, domestic 5 washing machine.

Figure 2 is a top plan view thereof.

Figure 3 is a transverse, horizontal section through the wringer on an enlarged scale, 0 the plane of the section being indicated by the line 3—3 of Figure 1.

Figure 4 is a longitudinal, vertical section through the clothes wringer, with parts shown in a position changed from that illustrated in Figure 1, the plane of the section being indicated by the line 4—4 of Figure 2.

Figures 5 and 6 are transverse, vertical sections through the clothes wringer in planes indicated by the lines 5—5 and 6—6 respectively, of Figure 1.

Figures 7 and 8 are fragmentary detail views illustrating the means for locking and unlocking the tension applying devices for the wringer rolls.

Referring now in detail to that embodiment of the invention, illustrated in the accompanying drawings, 10 indicates as a whole, a wringer frame which includes spaced apart, upright, hollow end standards 11—11^a, a bottom horizontal connecting bar 60 12 and a stationary top cross bar 13. Preferably as shown herein, the standards 11—11^a and the bottom connecting bar 12, are cast integral together with a hollow open top, hemi-spherical shell 14 located at the 65 outside bottom end of the standard 11. Said shell includes an annular, horizontal base, which is adapted for bearing engagement upon the top end of a bearing sleeve 15, on the frame 16 of a power driven, domestic 70 washing machine.

Through said bearing sleeve 15, extends an upright shaft 17, which is driven continuously in one direction by a suitable gearing such as is described in my co-pending 75 application filed on February 19, 1920, and which bears Serial No. 359,979.

The top end of the shaft 17 extends into the shell 14 and has therein, an upwardly facing bevel gear 18, a hemispherical top 80 cover 14^a closing the open top of said shell.

The upright hollow standards 11—11^a are preferably rectangular in plan and each includes upright front and rear side walls 19, inner and outer end walls 20, and an intermediate wall 21 parallel with the end walls to divide each hollow standard into an inner gear compartment 22 and an outer compression spring compartment 23. Each inner end wall 20 has near its top end, a dove tail 90 groove 24, into which fits the similar shaped ribs 25 on the ends of the top cross bar 13, said cross bar having a flat top wall 13^a and front and rear depending flanges 13^b (see Fig. 5). Suitable means are provided for 95 locking this cross bar in place against movement after the wringer has been assembled as a whole. All of the end and intermediate walls of said standards with the exception of the outer end wall of the right hand 100 standard 11^a as shown herein, have on their vertical median line, slots 27 which extend from a point near their bottom ends to the top thereof.

This construction provides for the insertion of both the bottom and top wringer rolls 28—29 and their respective shafts 30 and 31, said shafts extending through the

slots 27 as shown in Figs. 3 and 4. Each roll shaft has fixed thereto in the innermost compartment 22, intermeshing gears 32 and 33 respectively, of the usual kind. The 5 bottom wringer roll shaft 30 which is the longer, bears on the end and intermediate walls of the standards and has one end (the left hand end as shown) which extends into and also has bearing between the shell 14 and its cover 14^a. Within said shell, on said 10 shaft 30 is secured oppositely facing bevel pinions 35-35 which mesh with opposite sides of the gear 18 before mentioned, on the top end of the upright shaft 17. Each gear 15 35, has oppositely facing clutch teeth 36, which are adapted to be engaged by a clutch collar 37 keyed to the shaft 30 so as to be capable of being moved into engagement with either of its associated teeth on said 20 gears or into a neutral position between said gears. Shifting movement is imparted to this collar by a handle 38, mounted in the cover 14^a. Thus by shifting the collar 37, the wringer rolls may be stopped or started 25 and be caused to run in either direction at the will of the operator.

Tension is applied to the wringer rolls by means of the following construction: In each outermost compartment of the standards 11-11^a, is an inverted U-shaped yoke 40, which straddles and bears upon the ends of the top wringer roll shaft 31. The bottom ends of the upright legs of said yokes have horizontal flanges 41 into which are 30 threaded rods 42 (see Fig. 6) on the top ends of which is slidably mounted a cross bar 43, there being expansion coiled springs 44, surrounding each rod between said cross bar 35 and said bottom flanges.

40 In the top surfaces of said cross bars are provided recesses into which project the bottom ends of compression screws 45 which have threaded bearing in and near the outer ends of lever plates 46-47 respectively. 45 Each lever plate has at its outer end a pair of ears 48 which are pivoted on a pin 49 arranged at right angles to the wringer rolls and mounted in outwardly projecting ears 50 at the top end of the outer end 50 walls of standards 11, 11^a.

Each lever plate is of a length, equal to one-half the length of the wringer frame, so that when said plates are in their normal position, wherein they lay flat upon the 55 top cross bar 13, their inner ends will abut each other. Said lever plates are preferably shaped to conform with the plan area of the wringer frame and on the inner end of the lever plate 46 is provided flanges 52 which overhang the abutting end of the other lever plate 47. Near the inner end of the lever plate 46 is pivoted to swing about a vertical axis, a locking stem 53 which includes a handle 54 at its top end for actuating 60 the same. The bottom end of said stem 65

53 carries a foot, or key, 55, spaced from the lever plate a distance substantially equal to the thickness of the top wall of the bar 13, said foot including a radial extension or toe 56. A spring 57 as interposed between 70 said foot and the bottom surface of the lever plate 46.

In the top wall 13^a of the bar 13 is a keyhole-shaped opening 58, through which the foot 55 extends after which the handle 75 54 may be rotated to bring the toe 56 to engage the underside of said top wall 13^a to lock said lever plates to the said top bar. With the lever plates 46-47 thus locked in position upon the top bar 13, the screws 80 45 are actuated to exert a downward pressure on the cross bars 43 on the rods 42, which will, through the springs 44 on said rods, transmit pressure to the yokes through the bottom flanges, so as to bear upon the 85 top wringer roll shaft and force the top roll into snug contact with the bottom wringer roll.

When the shaft 15 is rotating, it will, when the clutch 37 is in engagement with either 90 bevel pinion 35 on the lower wringer roll shaft, drive said shaft in one or the other direction, the geared connection between said rolls driving the top roll.

Should it be necessary to quickly release 95 the tension on the wringer rolls, as when the clothing operated upon winds about one or the other rolls or should it happen that one hand of the operator becomes caught therein, it is only necessary to actuate the 100 handle 54 to bring the foot into register with the keyhole 58 in the top bar 13, when the tension of the springs will throw said levers upwardly about the pins 49, as an axis, permitting the springs to expand to 105 their full height, instantly releasing the tension so that a space or separation may be produced between the rolls and the clothing or hand removed therefrom. To reset the tension, the screws are unscrewed so that the 11 lever plates 46-47 may again bear throughout their length upon the top bar 13, and the handle 54, actuated to bring the toe 56 of the foot into that position shown in Fig. 7 wherein said lever plates are locked to 11 the top bar. The thumb screws 45 are again threaded through the said lever plates to apply pressure to the rolls as before described.

A reversible water board 60, is provided 12 beneath the bottom roll, said board having ears 61 at its ends, which are pivoted on a rod 62 extending the full length of the frame 10 near its bottom. Leaf springs 63, secured to said board and engaging said 13 rod, hold the board in either position so that the water expressed from the clothes may be diverted in either direction as it is desired.

It is apparent from the foregoing de- 1

scription that the improved wringer has many advantages. The tension on both ends of the wringer rolls may be instantly and simultaneously released. As the tension is applied near the outer pivoted ends of the lever plates, it is not absolutely necessary to fully unscrew the tension screws when resetting the lever plates 46—47, unless desired, because said plates provide the long leverage required to bear down on the adjoining ends of said lever plates, against the action of the springs 42, to bring them into a position wherein they may again be locked to the top bar.

5 10 15 The bottom bar and upright standards are all of metal providing a strong construction which is not affected by the water expressed from the clothes being operated upon. The wringer consists of but a few 20 parts which may be quickly and easily assembled by operators who need not be necessarily skilled in this line.

While in describing my invention, I have referred to certain details of mechanical construction and arrangement of parts, I do not wish to be limited thereto except as is pointed out in the appended claims.

I claim as my invention:—

1. In a clothes wringer, the combination 30 of a frame having upright end standards, a bar connecting the top ends of said standards, wringer rolls journaled in said standards, spring means therein providing a tension for said rolls, a two part device engaging 35 on the top of said top bar, pressure screws threaded through each of said device parts for imparting a tension to said spring means, and means carried by one of said device parts for locking and unlocking 40 both parts of said device to and from said bar connecting the top ends of the standards together.

2. In a clothes wringer, the combination 45 of a frame having upright end standards, a cross bar connecting the top ends of said standards, wringer rolls journaled in said end standards, spring means therein providing a tension for said rolls, lever plates normally engaging on said top cross bar, said plates being pivoted at their outer ends to said standards to swing about a horizontal axis at right angles to said wringer rolls, the inner ends of said lever plates meeting at the middle of the cross bar, pressure screws 50 threaded through said lever plates for imparting tension to said spring means, and means carried by the inner end of one of said plates for locking and unlocking the inner ends of both lever plates to and from said top cross bar.

3. In a clothes wringer, the combination 55 of a frame having upright end standards, a bar connecting the top ends of said standards, wringer rolls journaled in said end standards, spring means therein providing

a tension for said rolls, lever plates pivoted to said standards to swing about a horizontal axis at right angles to said wringer rolls, one of said lever plates having lugs which overhang the other lever plate, pressure 70 screws threaded through said lever plates near their pivoted ends, for imparting tension to said spring means, and a handle actuated locking member associated with said lever plate having said lugs for locking 75 and unlocking the inner ends of both lever plates to said top cross bar.

4. In a clothes wringer, the combination of a frame having upright end standards, a bar connecting the top ends of said standards, said bar having a keyhole opening therein near its middle, wringer rolls journaled in said end standards, spring means therein providing a tension for said rolls, lever plates pivoted to said standards 80 to swing about a horizontal axis at right angles to said wringer rolls, one of said lever plates having lugs at its inner end which overhang the adjoining end of the other lever plate, pressure screws threaded 85 through said lever plates for imparting tension to said spring means, a locking foot, including a toe, carried by that lever plate having the overhanging lugs, said foot being adapted to extend through said keyhole 90 opening and to be rotated into and out of registering positions with reference to said keyhole opening, and a handle also carried by said lever plate for actuating said locking foot.

5. In a clothes wringer, the combination of upright hollow end standards, each divided into inner and outer compartments, top and bottom wringer roll shafts journaled in said standards, intermeshing gears 105 near the ends of said shafts arranged in said inner compartments, a pair of tension springs in each outer compartment, the springs of each pair being arranged on opposite sides of each end of the top wringer roll shaft, means between said springs and the top wringer roll shaft for transmitting the tension of the springs thereto, and screws for regulating the tension of said springs.

6. In a clothes wringer, the combination of 115 a U-shaped frame comprising upright, hollow end standards and an integral bottom connecting bar, each standard being divided into inner and outer compartments, top and bottom wringer roll shafts journaled in said 120 standards, intermeshing gears fixed on said shafts in each inner compartment, tension means straddling the outer ends of the top wringer roll shaft in each outer compartment, and screws associated with said tension means for regulating the tension thereof.

7. A tension device for the rolls of a clothes wringer comprising, an inverted U-shaped yoke having outward extensions at 130

the bottom end thereof, upright rods carried by each extension, a cross bar slidable on the other ends of said rods, and an expansion coiled spring surrounding each rod between said cross bar and the extension on the bottom end of said inverted U-shaped yoke.

5 In testimony that I claim the foregoing

as my invention, I affix my signature in the presence of two witnesses, this 13th day of 10 February, A. D. 1920.

THOMAS H. MARS.
